CLAIM

The ornamental design for a card PC, as shown and described.

DESCRIPTION

FIG. 1 is an environmental view of a card PC with a docking station, showing our new design;

FIG. 2 is a top perspective view thereof;

FIG. 3 is a bottom perspective view thereof;

FIG. 4 is a top planar view thereof;

FIG. 5 is a bottom planar view thereof;

FIG. 6 is a left side planar view thereof;

FIG. 7 is a right side planar view thereof;

FIG. 8 is a front planar view thereof; and,

FIG. 9 is a back planar view thereof.

The stipple shading is for illustrative purposes to indicate a contrast in appearance and should not be confused with surface ornamentation.

(Continued)

Broken lines in the drawings are included for the purpose of illustrating environmental structure only and form no part of the claimed design.
